UNITED STATES PATENT OFFICE.

BENJAMIN F. DAVIS, OF SPUR, TEXAS.

BIT CLAMP.

Application filed September 30, 1920. Serial No. 418,674.

To all whom it may concern:

Be it known that I, BENJAMIN F. DAVIS, a citizen of the United States, residing at Spur, in the county of Dickens and State of Texas, have invented new and useful Improvements in Bit Clamps, of which the following is a specification.

This invention relates to oil well drilling apparatus and has for its object the provision of a clamping device adapted for association with the joints of drills or the like, which are commonly screwed together, and which is so constructed as to prevent any possible unscrewing and consequent separation of sections so as to avoid the delay and expense of fishing for broken tools or disconnected sections.

An important and more specific object is the provision of a connection of this character which includes a pair of clamping members detachably engageable upon sections of a drill or the like, the clamping members being formed at their meeting ends with interfitting tongues which will positively prevent any relative rotation of threadedly connected members.

An additional object is the provision of a device of this character which will be extremely simple and inexpensive in manufacture, highly efficient in use, durable in service, easy to apply, and a general improvement in the art.

With the above and other objects and advantages in view, the invention consists in the details of construction to be hereinafter more fully described and claimed, and illustrated in the accompanying drawings in which—

Figure 1 is a side elevation of my device applied to the meeting ends of drill sections,

Figure 2 is a cross sectional view, and

Figure 3 is a longitudinal sectional view.

Referring more particularly to the drawings, the letters A and B designate the sections of a drill or other device. In ordinary practice these sections are screwed together and it frequently occurs that from the continual jar of drilling the sections are relatively rotated and eventually become separated which necessitates the costly operation of fishing, by means of various tools, for the detached section or sections.

In carrying out my invention I provide a pair of members clamped upon each section

A and B of the drilling mechanism and each of these clamping members comprises substantially semi-cylindrical members 10 which are hingedly connected at one edge, as shown at 11, and which have their other edges formed with flanges 12 through which pass suitable clamping bolts 13. It will be observed that there are provided two sets of the members 10 which are identical in construction and which are clamped upon adjacent sections A and B of the drill. Formed upon the adjacent ends of the clamping members 10 are interfitting tongues 14 which are engaged when the sections or members 10 are applied and bolted into position. 70

When my clamping devices are in position as above described and as clearly shown, it will be seen that interengagement of the tongues 14 on the adjacent ends of the members 10 will positively prevent any relative rotation of the clamping members and consequently any possible relative rotation of the drill sections A and B. I have described the bolts as connecting the flanges 12 on the clamping members though it is 80 easily conceivable that I may employ any other suitable means for holding these clamping members in embracing engagement with the drill sections. 75

While I have shown and described the 85 preferred embodiment of my invention, it is of course to be understood that I reserve the right to make such changes in the form, construction, and arrangement of parts as will not depart from the spirit of the invention or the scope of the subjoined claim. 90

Having thus described my invention, I claim:

Means for securing together the sections of a well drilling rod, the ends of the rod 95 being formed with enlargements defining shoulders, comprising a plurality of similar clamping members engaged upon the enlargements and formed at their outer ends with inturned flanges engaging said 100 shoulders, said clamping members being formed at one edge with a plurality of interengaging pivotally connected knuckles and being provided at their other edges with flanges detachably connected, and the confronting edges of said clamping member being 105 formed with a plurality of interfitting tongues and grooves.

In testimony whereof I affix my signature.

BENJAMIN F. DAVIS.
